[57] CLAIM

The ornamental design for rear-view mirror mounting assembly, as shown and described.

DESCRIPTION

FIG. 1 is a top front perspective view of a rear-view mirror mounting assembly showing my new design in a position of use;

FIG. 2 is a front elevational view thereof;

FIG. 3 is a rear elevational view thereof;

FIG. 4 is a top view thereof;

FIG. 5 is a bottom view thereof;

FIG. 6 is a right side elevational view thereof;

FIG. 7 is a left side elevational view thereof;

FIG. 8 is a top front perspective view of FIG. 1 shown in a position of use with a second mirror and mirror housing;

FIG. 9 is a top front perspective view of FIG. 1 shown in a position of use with a third mirror and mirror housing;

FIG. 10 is a top front perspective view of FIG. 1 shown in a position of use with a fourth mirror and mirror housing;

FIG. 11 is a top front perspective view of FIG. 1 shown in a position of use with a fifth mirror and mirror housing;

FIG. 12 is a top front perspective view of FIG. 1 shown in a position of use with a sixth mirror and mirror housing; and,

FIG. 13 is a top front perspective view of FIG. 1 shown in a position of use with a seventh mirror and mirror housing.
